DESIGN FOR A BANNERET

Enrique Orta, Chicago, Ill.

Application February 23, 1943, Serial No. 109,610

Term of patent 3½ years

To all whom it may concern:

Be it known that I, Enrique Orta, a citizen of Mexico, residing at Chicago, in the county of Cook and State of Illinois, have invented a new, original, and ornamental Design for a Banneret, of which the following is the specification, reference being had to the accompanying drawing, forming part thereof, in which the figure is a front elevational view of a banneret, showing my new design.

I claim:

The ornamental design for a banneret, substantially as shown.

ENRIQUE ORTA.
